UNITED STATES PATENT OFFICE

104,677

DESIGN FOR A DRESS ENSEMBLE

Grace Diaz, New York, N. Y.

Application April 21, 1937, Serial No. 68,900

Term of patent 3½ years

To all whom it may concern:

Be it known that I, Grace Diaz, a citizen of the United States of America, residing in Manhattan, county of New York, and State of New York, have invented a new, original, and ornamental Design for a Dress Ensemble, of which the following is a specification, reference being had to the accompanying drawing, forming part thereof, wherein,

The arrangement of lace on the rear portion of the jacket unit is basically the same as is disclosed on the dress unit.

I claim:

The ornamental design for a dress ensemble, substantially as shown and described.

GRACE DIAZ.
